TOILET SEAT COVER

Edward Brooke, Jr., Birdsboro, Pa.

Application April 18, 1934, Serial No. 721,221

1 Claim. (CL 4—243)

This invention relates to an improved toilet seat cover, the purpose of the invention is to supply all public toilets with a sufficient quantity of covers to last an entire day, thereby furnishing each user with a clean sanitary surface to be occupied, warranting health and cleanliness.

Another purpose is to provide a device of this kind which is sanitary, and constructed of any suitable material preferably paper such as will 10 be of small compass when torn or folded and thrown in the hopper so as to pass off easily in the water.

Another purpose is to provide a toilet seat cover made entirely of such papers material as will be 15 suitable without any metallic fastening means whatever or without stickers of any kind, and yet so construct the toilet seat cover as to provide means for holding the cover in place as the user is in the act of assuming a sitting posture 20 thereon. As is well known the direction of movement of the user is downward and as a rule slightly rearwardly, and most seat covers heretofore have been provided with some attaching means at the rear, in which event the cover is very apt 25 to also move rearwardly, hence it is another purpose to provide an attaching means for the cover, as forming a part of the cover itself in conjunction with the bumpers on the under surface of the seat, thereby preventing the cover from moving 30 rearwardly with the movement of the body of the user.

Another purpose is to provide a toilet seat cover, the forward or lower leaf of the cover (due to the fact that these covers may be hung adjacent 35 the toilet seat on some suitable support, or otherwise arranged) to be folded under the seat and engaged between the bumpers or buffers (which ordinarily rest upon the porcelain bowl or hopper) and the edge of the bowl or hopper, 40 when the seat is lowered, thereby anchoring the cover in position and preventing its sliding movement rearwardly as the user assumes a sitting posture.

Another purpose is the provision of a cover of 45 this kind where the folded under leaf is provided with a V shaped cut out portion which is incident to the forward portion of the opening in the seat, thereby preventing any contact between the forward leaf of the cover and the user's person when 50 in sitting posture, the remote side portions of the leaf in this event engages between the bumpers or abutments (which are usually on the under surface of the seat) and the edge of the bowl or hopper.

55 It is to be understood that the particulars here-

in given are in no way limitative, and that while still keeping within the scope of the invention, any desired modification of details and proportions may be made in the construction of the appliance according to circumstances.

The invention comprises further features and combination of parts to be hereinafter set forth, shown in the drawing and claimed.

In the drawing:—

Figure 1 is a view of a portion of a hopper or 10 bowl including a toilet seat and illustrating the improved toilet seat cover as applied.

Figure 2 is a sectional view on line 2—2 of Figure 1 showing how the cover is arranged.

Figure 3 is a plan view of the cover in its 15 entirety.

Referring to the drawing 1 identifies the cover as a whole, and which may be made of any suitable paper material, such as will pass off with the water in the bowl or hopper in a small 20 compass.

It is obvious that the cover may be made of any dimensions such as will permit of its purposes and may be made of any shape preferably rectangular as shown. The cover has an opening 2, 25 substantially conforming to but smaller than the opening 3 in the toilet seat 4. This cover when applied is disposed upon the seat so that its opening will substantially register with the opening in the seat, in which event the forward leaf 7 30 of the cover may be folded under the forward end of the seat, in which case the remote side portions 8 may engage between the rubber bumpers 9 on the under surface of the seat and the edge of the bowl or hopper and by the disposition 35 of these remote sides the cover is prevented from moving rearwardly as the user is assuming a sitting posture.

These side portions are caused to be formed by providing the cover with a central cut out 40 portion 10, which may be of any suitable shape, the central cut out portion serving to avoid contact of the user's person with the cover when in service.

It is obvious that if preferred it is possible to 45 discard the used toilet seat covers in waste paper containers, such as those in which the paper towels are discarded, instead of disposing of the covers into the hopper.

The invention having been set forth, what is 50 claimed is:

A toilet seat cover comprising a single piece body of moisture absorbing material, whereby the cover may form into a small compass and pass off with the water in a hopper or bowl, said 55

body having an opening corresponding in shape and adapted to register with the opening in the seat, said body having a forward leaf provided with a centrally arranged cut out portion causing the side portions of the leaf to be formed, said side portions adapted to engage between the usual bumpers on the under surface of the seat and

the edge of the bowl or hopper, the central cut out portion adapted to substantially register with the forward portion of the opening in the seat, thereby avoiding contamination of the user's person by the user's person engaging with the front portion of the opening in the seat.
